(57) **CLAIM**

The ornamental design for a slip joint long nose pliers, as shown and described.

DESCRIPTION

FIG. 1 is a perspective view of a slip joint long nose pliers.

FIG. 2 is a perspective view from the opposite side of the pliers, shown in an alternate position of use.

FIG. 3 is a side view of the pliers.

FIG. 4 is an opposite side view of the pliers from FIG. 3.

FIG. 5 is a top view of the pliers.

FIG. 6 is a bottom view of the pliers.

FIG. 7 is an edge view of the pliers; and,

FIG. 8 is an opposite edge view of the pliers of FIG. 7.

The broken lines of FIGS. 1-8 are for illustrative purposes only and form no part of the claimed design.

The subject design is characterized by slip joint pliers having an extended and slender appearance.
